CLAIM

The ornamental design for the package collection device, as shown and described.

DESCRIPTION

FIG. 1 is a left-perspective view of a package collection device showing a first embodiment of our new design;

FIG. 2 is a left-side view of the first embodiment of our new design;

FIG. 3 is a right-side view of the first embodiment of our new design;

FIG. 4 is a top view of the first embodiment of our new design, the bottom of the device not being visible during its intended use;

FIG. 5 is a front view of the first embodiment of our new design;

FIG. 6 is a rear view of the first embodiment of our new design; and,

FIG. 7 is a left perspective view of a second embodiment of a package collection device, the only difference being the color blue.

The drawing of FIG. 7 is lined for color, specifically the color blue.
